DESIGN FOR A DRESS ENSEMBLE

Zelma Golden, Larchmont, N. Y.

Application December 18, 1940, Serial No. 97,410

Term of patent 3½ years

To all whom it may concern:

Be it known that I, Zelma Golden, a citizen of the United States, residing at 22 Dimitri Place, Larchmont, in the county of Westchester and State of New York, have invented a new, original, and ornamental Design for a Dress Ensemble, of which the following is a specification, reference being had to the accompanying drawing, forming part thereof.

Figure 1 is a front view of a dress ensemble, showing my new design;

Figure 2 is a rear view of Figure 1;

Figure 3 is a fragmentary front view of the upper portion of the dress ensemble shown in Figure 1; and

Figure 4 is a rear view of Figure 3.

The characteristic feature of my design resides in the combination on the ensemble disclosed of the specific jacket member having wide, double lapels and a yoked and seamed back, in association with the surplice dress having contrastingly colored sleeves, sash, and front blouse portions, and the particular skirt, all as shown.

I claim:

The ornamental design for a dress ensemble, substantially as shown and described.

ZELMA GOLDEN.
